UNITED STATES PATENT OFFICE.

HENRY ALEXANDER WICKHAM, OF LONDON, ENGLAND.

APPARATUS FOR TREATING LATEX.

1,720,827.

Specification of Letters Patent. Patented Jan. 26, 1915.

Application filed April 27, 1914. Serial No. 234,872.

To all whom it may concern:

Be it known that I, HENRY ALEXANDER WICKHAM, a subject of the King of England, residing in London, England, have invented certain new and useful improvements in Apparatus for Treating Latex, of which the following is a specification.

This invention relates to improvements in apparatus for treating latex, the apparatus being of the type in which there is employed a rotating device, for example a rotating cylinder, adapted to produce and expose successive thin films of latex to the action of a treating agent.

According to the present invention apparatus of the type referred to is combined with a housing completely or partially inclosing the rotating member and a partition therein dividing the casing into two compartments, to one of which compartments the treating agent is admitted while the partition largely or mainly isolates the other compartment from the treating agent. Preferably the construction is such that at one portion of the housing there is an opening to provide means of access to the rotating member.

A feature of the invention consists in the employment of a latex-delivery conduit whose outlet is adapted to discharge on to the latex-receiving surface of the rotating member combined with means to move the delivery end of the said conduit across the face of the said receiving surface to distribute the latex thereon. In a preferred construction there is a single operating member having operative connections between it and the rotating member and the latex-delivery conduit whereby the required movements are imparted to the said rotating member and to the conduit. In a modified construction of the apparatus the latex-receiving surface is constituted by a horizontally-disposed rotating member, for example a flanged plate or the like. Or it may be a member rotating about a perpendicular axis.

The invention will be better understood by reference to the following description taken in connection with the accompanying drawings which illustrate preferred embodiments of the invention, and in which—

Figure 1 is a front elevation of one type of apparatus according to the invention; Fig. 2 is a part sectional elevation on the line 2—2 of Fig. 1; Fig. 3 is a diagram-

matic plan of the operating mechanism for the latex-delivery conduit, the parts being shown in one plane; Fig. 4 is a central sectional elevation of a modified form of the apparatus; Fig. 5 is a plan of the apparatus shown in Fig. 4; Fig. 6 shows an apparatus provided with a heating jacket, and Fig. 7 is a diagrammatic illustration of a modified construction of apparatus.

Like letters indicate like parts throughout the drawings.

Referring to Figs. 1-3 the members on to which the latex is fed and upon which it is treated comprises a rotating cylindrical trough A mounted for rotation on the shaft B by means of a boss A¹ having a supporting spider referred to generally by the reference letter A². The member A is provided with an inclosing casing C which, except for a portion C¹, completely incloses it. The casing C is supported by a suitable framework D and is provided with two sliding partitions E and E¹. The partition E is situated midway in the casing as illustrated and extends within the member A across the space between the inwardly projecting flange A³. The partition E¹ is disposed below the partition E and also extends within the member A across the chord bounded by the flange A³. A smoke-producing furnace F is situated outside the casing C and conveys smoke to the interior of the member A through a flue F¹ having a telescopic portion F² to enable the furnace to be placed at desired distances from the casing C, and having also a spherical joint F³. A damper F⁴, in the form of a disk, is provided to control the flow of smoke from the furnace F to the flue F¹. The outlet F⁵, as shown more particularly in Fig. 1, is directed toward the cylindrical wall of the trough A upon which, as will be hereinafter described, the latex is carried in successive thin films. The casing C is provided with a shaft or chimney C² into which opens a by-pass flue F⁶ from the furnace F the flue having a telescopic portion at F⁷, a spherical joint at F⁸ and a damper F⁹. The latex to be treated is charged into the reservoir G which has an outlet G¹ controlled by a cock G². The outlet G¹ discharges into a trough-like conduit H whose delivery end H¹ discharges on to the cylindrical surface of the trough as indicated in the drawings. It is desired that the delivery end H¹ of the trough H should

be moved laterally across the cylindrical

surface to distribute the latex evenly thereon. For this purpose the shaft B is connected by a belt J to another shaft J¹ having flexible joints at J² and terminating in a worm J³. The end of the shaft J¹ near the worm J³ is supported in an arm J⁴ of the bracket J⁵ supported on the machine-frame D. Meshing with the worm J³ is a worm-wheel K having on its upper face a slot K¹ in which travels a pin K² projecting from a portion H² of the trough-member H. The part H² is adapted to receive between it and the trough H anti-friction supports H³ carried on an arm J⁶ extending from the bracket J⁵. The shaft B may be belt-driven, for which purpose fast and loose pulleys, illustrated at B¹, are provided to receive the belt. Alternatively the shaft B may be manually rotated by means of the crank-handle B² and gearing B³, B⁴.

The operation of the apparatus above described is as follows:—The shaft B is rotated and with it the member A¹ and the shaft J¹. Latex is supplied at the desired rate from the reservoir G to the trough H and from it to the member A. Owing to the rotation of the shaft J¹ the worm-wheel K is rotated and the cam-groove K¹ reciprocates the trough H by its connection through the pin K². The bearings H² also serve as guides cooperating with the part H² to restrain the movement of the trough H so that it passes across the surface of the member A and parallel to it. Smoke is admitted from the smoke-producing furnace through the flue F¹ and the discharge opening F² so that it impinges upon the latex which has been supplied to the member A and carried around by it. The end of the flue F¹ projects through a slide F¹⁰ moving in guides on the casing so that the position of the outlet F² relatively to the latex-receiving surface may be adjusted as desired. By means of the partitions E and E¹ the smoke is largely isolated from that portion of the casing below the partition E¹ and open at O¹. Thus the operator has access to the layer of latex as it is carried around by the cylinder A without sufficient smoke being carried toward him to cause him inconvenience. The member A is rotated generally at the rate of from 60-80 revolutions per minute and during the rotation the latex becomes spread out in a thin film over the surface of the member. The layers of latex as they are produced are carried around into contact with the smoke in a direction indicated by the arrow in Fig. 1 and are cured and hardened by the action of the smoke. When the successive layers of latex have accumulated to the required depth the smoke is cut off from the flue F¹ by means of the damper F⁴ and the damper F² is opened to allow the smoke to ascend through the flue F² directly to the chimney C² thus al-

lowing the contents of the furnace to continue to burn.

In Figs. 4 and 5 a modified form of apparatus is illustrated in which the latex is supplied to a horizontally-disposed carrier. The carrier comprises a circular plate L having a flange L¹ to which latex is supplied from a reservoir M through a conduit M¹ which is adapted to be swung across the surface of the plate L by means of the cam-member O, pivoted lever O¹ and connecting rod O². The trough M¹ is pivotally mounted at M² to allow this movement. A casing L², open at L³, incloses the flanged plate L. Smoke is led through the flue P through a downwardly directed discharge opening P¹ on to the surface of the latex which has been spread on the plate L. The smoke escapes through an uptake P², and a baffle L⁴ is provided to screen the smoke-chamber from the opening L³ in a similar manner to the action of the baffle E¹ in Figs. 1 and 2. The plate L is rotated from a shaft Q through a gear Q¹ co-acting with a rack Q² and operated either by hand or by a belt-drive or other convenient means. Anti-friction bearings L⁵ are provided to facilitate the running of the plate L. If the plate is rotated slowly latex may be cured upon the surface L, but generally speaking the plate is rotated at such a rate that the latex flows on to the cylindrical flange L¹, in which case the smoke-outlet P¹ would discharge directly on to the flange L¹ as shown in dotted lines at P³.

The operation of the apparatus illustrated in Figs. 4 and 5 is similar to that of the apparatus described in connection with Figs. 1-3 and will not need further explanation herein.

In either of the constructions illustrated there may be provided, if necessary, a jacket surrounding the casing C or L² which may be employed as a heating jacket by the introduction of smoke, steam or other heating medium thereto. This has been shown in Fig. 6 as applied to an apparatus similar to that described in connection with Figs. 1-3, the jacket being denoted by C².

Obviously the latex-receiving surfaces described herein may be substituted by an elongated endless band traveling within a suitable housing or smoke-chamber. Thus, in Fig. 7 there has been shown diagrammatically a construction of apparatus in which an endless belt R provided with side-plates R¹ is arranged to be supported on rotatable drums or the like R² within a casing R³ having an uptake R⁴ and a smoke-inlet pipe R⁵. A latex-delivery conduit and its cooperating mechanism for moving it transversely across the belt to distribute the latex evenly thereon, is referred to generally by the reference letter R⁶ and operates in a similar manner to the delivery conduit 110

shown in connection with the construction according to Figs. 1-3.

Although two constructions of the apparatus have been described in detail the invention is not limited to the particular details shown as these may be varied provided that the spirit of the invention is not departed from.

What I claim as my invention and desire 10 to secure by Letters Patent is:—

1. Apparatus for treating latex comprising in combination, a member providing a traveling latex-receiving surface, a housing surrounding said member, a partition arranged within the housing to divide it into two compartments, means to admit the treating agent to one of the compartments while the other compartment is mainly isolated from the treating agent by means of the 20 partition, and a heating jacket surrounding the housing.

2. Apparatus for treating latex comprising in combination, a member providing a traveling latex-receiving surface, a housing 25 surrounding the receiving-member, a slideable partition disposed within the housing to divide it into two compartments and means to admit a treating agent to one of the compartments while the other compartment is mainly isolated from the treating agent by the partition.

3. Apparatus for treating latex comprising in combination, a member providing a traveling latex-receiving surface, a housing 35 surrounding said member to partially inclose it, there being an opening at one portion thereof to afford means of access to the aforesaid latex-receiving surface, a partition arranged within the housing to divide it into two compartments so that the aforesaid opening is disposed in one of them and means to admit the treating agent to the other compartment.

4. Apparatus for treating latex comprising in combination, a member providing a traveling latex-receiving surface, a housing 45 partially inclosing said member and providing an opening at one portion to afford means of access to the aforesaid latex-receiving member, a partition arranged within the housing to divide it into two compartments so that the aforesaid opening is disposed in one of them, means to admit the treating agent to the other compartment 55 and a heating jacket surrounding the housing.

5. In apparatus for the treatment of latex, the provision of a member providing a traveling latex-receiving surface combined with 60 a latex-delivery conduit whose outlet discharges on to the latex-receiving surface and means to move the delivery end of the said conduit transversely across the face of the said receiving-surface for the purpose of distributing latex thereon.

6. In apparatus for treating latex the provision of a member providing a traveling latex-receiving surface and a housing surrounding the said member combined with a latex-delivery conduit whose discharge end 70 protrudes through the casing and is arranged to discharge on to the latex-receiving surface, a latex-reservoir disposed outside the housing and arranged to discharge its contents into the latex-delivery conduit and means to move the delivery end of the conduit transversely across the face of the latex-receiving surface for the purpose of distributing latex thereon.

7. In apparatus for treating latex the provision of a member providing a traveling latex-receiving surface combined with a latex-delivery conduit arranged to discharge on to the latex-receiving surface, means to move the delivery end of the said conduit 80 transversely across the face of the said receiving-surface for the purpose of distributing latex thereon and a single operating member and operative connections between it and the aforesaid latex-receiving member 85 and the delivery conduit to move the said receiving-member and to cause the delivery end of the latex-delivery conduit to move across the face of the said receiving-surface.

8. Apparatus for treating latex comprising in combination, a member providing a traveling latex-receiving surface, a housing surrounding the receiving-member, a partition disposed within the housing to divide it into two compartments, means to admit a 100 treating agent to one of the compartments while the other compartment is mainly isolated from the treating agent by the partition, a latex-delivery conduit whose outlet 105 discharges on to the latex-receiving surface and means to move the delivery end of the said conduit across the face of the said receiving-surface for the purpose of distributing latex thereon.

9. Apparatus for treating latex comprising in combination, a member providing a traveling latex-receiving surface, a housing surrounding the receiving member, a slideable partition disposed within the housing to divide it into two compartments, means 110 to admit a treating agent to one of the compartments while the other compartment is mainly isolated from the treating agent by the partition, a latex-delivery conduit whose outlet 115 discharges on to the latex-receiving surface and means to move the delivery end of the said conduit across the face of the said receiving-surface for the purpose of distributing latex thereon.

10. Apparatus for treating latex comprising in combination, a member providing a traveling latex-receiving surface, a housing surrounding the receiving-member, a partition disposed within the housing to divide it into two compartments, means to 120

admit a treating agent to one of the compartments while the other compartment is mainly isolated from the treating agent by the partition, a latex-delivery conduit whose outlet discharges on to the latex-receiving surface, means to move the delivery end of the said conduit across the face of the said receiving-surface for the purpose of distributing latex thereon, and a heating jacket surrounding the housing.

11. Apparatus for treating latex comprising in combination, a member providing a traveling latex-receiving surface, a housing partially inclosing said member and providing an opening at one portion to afford means of access to the aforesaid latex-receiving surface, a partition arranged within the housing to divide it into two compartments so that the aforesaid opening is disposed in one of them, means to admit the treating agent to the other compartment, a latex-delivery conduit whose outlet discharges on to the latex-receiving surface and means to move the delivery end of the said conduit across the face of the said receiving-surface for the purpose of distributing latex thereon.

12. Apparatus for treating latex comprising in combination, a member providing a latex-receiving surface, a housing surrounding the receiving member, a partition disposed within the housing to divide it into two compartments, means to admit a treating agent to one of the compartments, a latex-delivery trough whose discharge end protrudes through the casing and is arranged to discharge on to the latex-receiving surface, a latex-reservoir disposed outside the housing and arranged to discharge its contents into the latex-delivery trough, and means to move the delivery end of the trough across the face of the latex-receiving surface for the purpose of distributing latex thereon.

13. Apparatus for treating latex comprising in combination, a rotating drum-like member providing a latex-receiving surface, a housing surrounding the said member and providing a segmental opening at one portion thereof to afford means of access to the aforesaid latex-receiving surface, a partition arranged within the housing to divide it into two compartments so that the aforesaid opening is disposed mainly in one of them, means to admit the treating agent to the other compartment and a second partition extending within the casing and forming a chord-like boundary across the said segmental opening.

14. Apparatus for treating latex comprising in combination, a rotating drum-like member providing a latex-receiving surface, a housing surrounding the said member and providing a segmental opening at one portion thereof to afford means of access to the

aforesaid latex-receiving surface, a partition arranged within the housing to divide it into two compartments so that the aforesaid opening is disposed mainly in one of them, means to admit the treating agent to the other compartment, a second partition extending within the casing and forming a chord-like boundary across the said segmental opening, a latex-delivery conduit whose outlet discharges on to the latex-receiving surface, and means to move the delivery end of said conduit across the face of the receiving-surface for the purpose of distributing latex thereon.

15. Apparatus for treating latex comprising in combination, a rotating drum-like member providing a latex-receiving surface, a housing surrounding the said member and providing a segmental opening at one portion thereof to afford means of access to the aforesaid latex-receiving surface, a slideable partition arranged within the housing to divide it into two compartments so that the aforesaid opening is disposed mainly in one of them, means to admit the treating agent to the other compartment, a second slideable partition extending within the casing and forming a chord-like boundary across the said segmental opening, a latex-delivery conduit whose outlet discharges on to the latex-receiving surface, and means to move the delivery end of said conduit across the face of the receiving surface for the purpose of distributing latex thereon.

16. Apparatus for treating latex comprising in combination, a drum-like member rotating about a horizontal axis and providing a latex-receiving surface, a housing surrounding the said member and providing a segmental opening at one portion thereof to afford means of access to the aforesaid latex-receiving surface, a partition arranged within the housing to divide it into two compartments so that the aforesaid opening is disposed mainly in one of them, means to admit the treating agent to the other compartment and a second partition extending within the casing and forming a chord-like boundary across the segmental opening.

17. Apparatus for treating latex comprising in combination, a drum-like member rotating about a vertical axis and providing a latex-receiving surface, a housing surrounding the said member and providing a segmental opening at one portion thereof to afford means of access to the aforesaid latex-receiving surface, a partition arranged within the housing to divide it into two compartments so that the aforesaid opening is disposed mainly in one of them, means to admit the treating agent to the other compartment and a second partition extending within the casing and forming a chord-like boundary across the segmental opening.

18. In apparatus for treating latex the

- provision of a member providing a traveling latex-receiving surface and combined with a latex-delivery conduit arranged to discharge on to the latex-receiving surface, means to 5 move the delivery end of the said conduit across the face of the said receiving-surface for the purpose of distributing latex thereon, a rotating shaft connected to rotate the latex-receiving member and connected also with a 10 worm and worm-wheel, the latter having a cam-groove in its circular face, and a connection between the latex-delivery conduit and the cam-groove whereby the discharge end of the conduit is moved across the face 15 of the said latex-receiving surface.
19. Apparatus for treating latex comprising in combination, a member providing a traveling latex-receiving surface, a housing surrounding the receiving member, an uptake 20 flue in connection with the housing, a smoke-producing furnace disposed outside the housing, a damper-controlled smoke-conduit leading from the smoke-producing furnace
- to within the housing and discharging on to the latex-receiving surface and another 25 damper-controlled conduit connecting between the smoke-producing furnace and the uptake flue, a partition disposed within the housing to divide it into two compartments whereby one of the compartments receives 30 smoke from the smoke-conduit and the other is mainly isolated from the smoke by means of the partition, a latex-delivery conduit whose outlet discharges onto the latex-receiving surface and means to move the delivery end of the said conduit across the face of the said receiving-surface for the purpose of distributing latex thereon. 35
- In testimony whereof I have signed my name to this specification in the presence of 40 two subscribing witnesses.
